CLAIM

The ornamental design for a key, as shown and described.

DESCRIPTION

FIG. 1 is a perspective view from the front side of a key.

FIG. 2 is a perspective view from the rear side thereof.

FIG. 3 is a front elevation view thereof. A rear elevation view is identical to the front elevation view.

FIG. 4 is a left side elevation view thereof. A right side elevation view is identical to the left side elevation view.

FIG. 5 is a top plan view thereof; and,

FIG. 6 is a bottom plan view thereof.

The portion of the key shown in broken lines is for the purpose of showing environmental structure only and forms no part of the claimed design.
